[57] **CLAIM**

The ornamental design for a liquid siphon for aquariums, as shown and described.

DESCRIPTION

FIG. 1 is a perspective view of a liquid siphon for aquariums showing my new design;
FIG. 2 is a front elevational view thereof;
FIG. 3 is a rear elevational view thereof;
FIG. 4 is a side elevational view thereof;
FIG. 5 is an opposite side elevational view thereof;
FIG. 6 is a top plan view thereof;
FIG. 7 is a bottom plan view thereof.
The broken away portion on the tube in FIGS. 1, 4-7 is to indicate an indeterminate length.

FIG 3

FIG 2

FIG. 4

FIG. 5
